UNITED STATES PATENT OFFICE

WILLIAM H. GEROU, OF PHILADELPHIA, PENNSYLVANIA, ASSIGNOR TO SELF LIGHTING CIGARETTE CORPORATION OF AMERICA, A CORPORATION OF DELAWARE

CIGARETTE LIGHTER

Application filed July 23, 1931. Serial No. 552,787.

This invention pertains to cigarette lighters of that class in which the lighter is carried on the lighting end of the cigarette, such as is generally known as self-lighting cigarettes, and the invention is equally applicable to cigars.

The main object of the invention is to provide simple, economical, practical and thoroughly efficient means attached to the end 10 of a cigarette, said means consisting of a coating of pyrophoric material on the outside of the lighting end of the cigarette, and a sleeve so disposed around said end that when it is slid off the end of the cigarette, the 15 igniting material on the inside of the sleeve comes into close frictional contact with the pyrophoric material on the outside of the cigarette, thereby causing same to ignite and light the cigarette.

20 Another object of the invention is to so dispose my improved lighting means with relation to the cigarette that it prevents the lighting material from contacting with the tobacco or extending into the body of the cigarette, and at the same time prevents any 25 premature or accidental light of the cigarette.

Further objects of the invention are to so 30 construct the novel lighting means that the sleeve carrying the igniting material must be intentionally forced off the cigarette by being pulled therefrom to light the cigarette; that it is definitely held in a position where it cannot ignite until it is forcibly pulled off the end of the device, and that it is easy 35 to manufacture by machine, and can be attached to the cigarette without being touched by hand.

The foregoing and such other objects as 40 may appear from the ensuing description are accomplished by the construction, arrangement, location and combination of the several parts hereinafter more fully described, illustrated in the accompanying drawing, and more particularly pointed out in the claims 45 appended hereto, it being understood that slight changes in the precise shape, proportions and minor details of construction may be resorted to without departing from the spirit or sacrificing any of the advantages 50 of the invention.

In the accompanying drawing forming a part of this specification it will be seen that:

Figure 1 is a perspective of a cigarette showing the novel lighting means embodying my invention.

Figure 2 is an enlarged view showing in part an elevation of a cigarette broken away, and showing the upper end portion and lighting means in cross-section.

Figure 3 is an enlarged view showing a 60 cigarette broken away in elevation and the top portion of the cigarette in perspective with the lighting means surrounding its upper or lighting end, and

Figure 4 is an enlarged perspective showing 65 the igniting sleeve detached from the cigarette.

In the embodiment of my invention as illustrated it will be seen that the numeral 2 designates a cigarette of the usual or well 70 known formation, said cigarette being coated on the outside of its lighting end with a suitable pyrophoric material 3, preferably such as is used in safety match heads, while 4 indicates a detachable sleeve preferably made 75 of thin cardboard or other suitable flexible material which is fitted snugly over the outside of the lighting end of the cigarette and surrounding the pyrophoric material, and below said material the said sleeve is slightly 80 reduced in its diameter at 5 to its lower end portion, the inner face of the lower end portion being provided with a suitable coating of igniting substance 6, such as is usually used on the side of a safety match box.

85 It will be perceived that since the end of the cigarette is coated on the outside with pyrophoric material, the sleeve 4 is so arranged that when it is slid off the end of the cigarette, the igniting substance 6 on the inside of the sleeve comes into close frictional contact with the pyrophoric material, thereby causing same to ignite and light the cigarette, the sleeve being formed of flexible material so that it may be slightly compressed 90 by squeezing with the fingers of the smoker as it is withdrawn over the pyrophoric material, thus allowing the smoker to increase the pressure and friction as the sleeve is slid off the cigarette, thereby regulating the pres- 95 100

sure to whatever degree may be necessary or desired as the igniting and pyrophoric materials come into frictional contact.

In order to prevent these surfaces from coming into contact before it is desired to light the cigarette the sleeve is so constructed that it fits around the body of the cigarette tightly enough to prevent its slipping or sliding without pressure, since by simply 10 making the sleeve fit tightly, and by having a slightly reduced diameter about midway of the sleeve it serves to grip the cigarette tight enough to prevent the sleeve being slid without force, and thus holds the igniting material away from the pyrophoric material until the sleeve is intentionally pulled or slid off the cigarette.

The diameter of the sleeve 4 at the point where it is coated with the igniting material 20 is made smaller than the diameter of the cigarette at the point where it carries the pyrophoric material, hence, as the sleeve is pulled or forced off the cigarette the igniting and the pyrophoric materials are sure to 25 come into tight frictional contact even though there were no pressure put on the sleeve by the smoker's finger, and the cigarette being of a soft, springy nature it naturally compresses enough to permit the 30 smaller diameter of the sleeve, at the point where the igniting material is carried, to pass over the larger diameter of the pyrophoric material carried by the cigarette. The said sleeve 4 may also carry the directions, name 35 or any other advertising matter of the maker, and may be provided on its outer face with circular grooves or any suitable formation of roughness that would serve to prevent its slipping from the fingers of the smoker when 40 pulled.

It will be readily obvious that by the construction and arrangement of my improved lighter it is definitely held in a position where it cannot ignite until it is forcibly pulled off 45 the end of the cigarette.

While my invention is shown and preferably made with slightly reduced diameter between the two ends of the slidable sleeve, it will nevertheless work perfectly if made 50 in cylindrical form of one diameter throughout or in almost any other form that enables the sleeve to fit the body of the cigarette sufficiently tight to prevent it being slid unintentionally, yet retains the essential feature 55 of holding the igniting material carried by the sleeve and the pyrophoric material carried by the end of the cigarette spaced apart until the sleeve is forcibly pulled.

Having thus described my invention what 60 I claim and desire to secure by Letters Patent is:

1. A self-lighting cigarette carrying a pyrophoric material on its end, and a flexible open ended sleeve carrying igniting material, with means for holding these two 65

materials apart until the sleeve is intentionally pulled from the cigarette.

2. A self-lighting cigarette carrying pyrophoric material on its end, also a flexible sleeve open at each end thereof carrying 70 igniting material for the purpose of igniting the cigarette when the sleeve is intentionally pulled therefrom.

3. A self-lighting cigarette carrying a circular band of pyrophoric material on its 75 outside surface at the end thereof, and a sliding sleeve open at each end carrying a circular band of igniting material on its inside surface at the lower end portion of said sleeve furthest from the pyrophoric mate- 80 rial.

4. A self-lighting cigarette carrying pyrophoric material around its outer surface at one end and a flexible sleeve open at each 85 end carrying igniting material at its lower end portion adapted to slide over and make frictional contact with the pyrophoric material when the sleeve is intentionally pulled from the cigarette, said sleeve being sufficiently flexible to allow the pressure of the 90 smoker's finger to compress the sleeve as it is withdrawn, thereby increasing the pressure of the igniting and pyrophoric materials as the sleeve is pulled.

5. A self-lighting cigarette carrying a circular band of pyrophoric material on its outside at the end thereof, and a sliding sleeve open at each end carrying a circular band of igniting material on its inside at 95 the lower end portion of the sleeve furthest away from the pyrophoric material with means for holding the igniting material and pyrophoric material apart from each other until the sleeve is intentionally pulled over the end of the cigarette.

6. A self-lighting cigarette carrying a circular band of pyrophoric material on its outside at the end thereof, and a sliding sleeve embracing the lighting end of the cigarette carrying a circular band of igniting 110 material on its inside at the lower end portion of the sleeve furthest away from the pyrophoric material with means for holding the igniting material and the pyrophoric material apart from each other until the sleeve is intentionally pulled over the end 115 of the cigarette, said sleeve being flexible so that it may be compressed by the pressure of the fingers as the sleeve is pulled.

7. A self-lighting cigarette, comprising a 120 coating of pyrophoric material on its outside at one end, and a slidable open ended sleeve surrounding said material, said sleeve having a band of igniting material formed on its inner face at its lower end portion 125 disposed a suitable distance from the pyrophoric material to prevent contact until desired.

8. A self-lighting cigarette of the character described, comprising a circular band 130

of pyrophoric material on its outside at the end thereof, and a slidable sleeve embracing said material, said sleeve being formed with a reduced diameter below the material and with a band of igniting material on its inner face at its lower end portion for maintaining the said materials at a suitable distance apart.

9. A self-lighting cigarette, comprising a ring of pyrophoric material formed on its outside, and a slidable sleeve embracing said material formed with a reduced diameter at its lower end, and a coating of igniting material formed on its inner face at said lower end whereby the said materials are maintained at a suitable distance apart.

10. A self-lighting cigarette, comprising a coating of pyrophoric material disposed around the outer surface of the cigarette, and a slidable sleeve disposed around said material, said sleeve being formed with means disposed below the pyrophoric material to prevent its accidental sliding and with a coating of igniting material on its inner face at its lower end portion whereby the said materials are separated at a suitable distance apart.

11. A self-lighting cigarette of the character described, comprising a band of pyrophoric material formed around the outside of the cigarette, and a slidable sleeve open at each end surrounding said material, said sleeve being formed with a reduced diameter extending from the material to its lower end, and with a band of igniting material on its inner face at its lower end adapted to hold the said materials separated at a suitable distance apart.

12. A self-lighting cigarette carrying pyrophoric material and a sleeve open at each end thereof and carrying igniting material for the purpose of lighting the cigarette.

13. A self-lighting cigarette carrying pyrophoric material and an open ended sleeve carrying igniting material with means for holding these materials apart until the sleeve is pulled for the purpose of lighting the cigarette.

14. A self-lighting cigarette carrying pyrophoric material and a movable surrounding sleeve open at each end thereof carried on its outside at one end of the cigarette, said movable sleeve carrying igniting material, and means for holding the pyrophoric and igniting materials apart until the cigarette is to be lit.

WILLIAM H. GEROU.
